UNITED STATES PATENT OFFICE.

EARL E. CRONENWETH, OF WILKINSBURG, PENNSYLVANIA.

SPRING OILER.

Application filed March 27, 1922. Serial No. 547,078.

To all whom it may concern:

Be it known that I, EARL E. CRONENWETH, a citizen of the United States, residing at Wilkinsburg, in the county of Allegheny and State of Pennsylvania, have invented new and useful Improvements in Spring Oilers, of which the following is a specification.

This invention relates to an oiling device 10 for use upon the springs of vehicles, the general object of the invention being to provide an oil reservoir which will keep the springs supplied with oil.

Another object of the invention is to provide means whereby the movement of the springs will act to distribute the oil between the leaves of the spring.

This invention also consists in certain other features of construction and in the 20 combination and arrangement of the several parts, to be hereinafter fully described, illustrated in the accompanying drawings and specifically pointed out in the appended claim.

25 In describing my invention in detail, reference will be had to the accompanying drawings wherein like characters denote like or corresponding parts throughout the several views, and in which;—

30 Figure 1 is a side view showing the invention applied upon a spring.

Figure 2 is a longitudinal sectional view through the device.

Figure 3 is a sectional view taken on line 35 3—3 of Figure 1.

Figure 4 is a sectional view taken on line 4—4 of Figure 5.

Figure 5 is a sectional view taken on line 5—5 of Figure 1.

40 Figure 6 is a perspective view of an end spring member.

As shown in these views the device consists of a trough shaped part 1 which encloses the bottom and sides of the spring 45 which is shown at A. The trough shaped member is of tapered shape so as to conform to the shape of the spring and it is provided with a cover 2 which is removably held to the sides by the latches 3. This

50 cover is provided with a filling opening which is closed by a screw cap 4. Thus oil can be placed in the device without removing it from the spring. At each end of the device is located a strip 5, of felt or the like, which acts to prevent the oil from escaping from the ends of the device. The

device is also provided with a lining 6 which extends over the sides, top and bottom and acts to hold the oil and to distribute it to the leaves of the spring. An oil reservoir 60 7 is formed in the bottom of the device to act as a reservoir and extra supply of oil. This sump may be filled with absorbent material if desired. A yoke-shaped member 8, formed of spring metal, is placed in each 65 end of the device and rod 9 connects the upper ends of each yoke together above the spring. The strips 5 are each formed of one piece with the ends placed on the top of the spring, as shown at 5'. Leaf springs 70 10 are placed on these strips and under the rods 9, these springs 10 acting to force the yokes upwardly and said yokes act to compress the sides and bottom of the device upon the felt strips 5 and thus prevent leakage 75 at the upper ends of the device. The cover is provided with raised portions for converging the ends of the yokes and their holding rods.

I provide spring latch bars 11 on the part 80 1 for engaging keeper members 12 on the cover for holding said cover in position. These latch members may be used in addition to the latches 3 or said latches 3 may be omitted when the members 11 and 12 are 85 used. These spring latch members 12 will allow the lid to move up with the springs or down as the case may be.

From the above it will be seen that the expansion and contraction of the spring will 90 act to force the oil in the device to all parts of the spring, thus keeping the leaves thereof thoroughly lubricated. The device can be easily filled with oil and very little of the oil can escape from the device due to the 95 packing at the ends thereof and the spring yokes which serve to compress the packing.

It is thought from the foregoing description that the advantages and novel features of my invention will be readily apparent.

I desire it to be understood that I may make changes in the construction and in the combination and arrangement of the several parts, provided that such changes fall within the scope of the appended claim.

100 What I claim is:—

A spring oiler of the class described comprising a trough shaped member, a detachable cover therefor, a filling opening in the cover, packing strips at the ends of the member, yoke shaped members of spring material engaging the ends of the trough 110

shaped member for compressing the packing strips, spring means for holding the yoke shaped members in place, a lining of absorbent material for the trough shaped member, an off set portion formed in the bottom of said member providing an oil reservoir, a keeper laterally disposed from the cover and a spring latch bar rigidly se-

cured to the trough shaped member and having engagement with the keeper so as to allow the trough shaped member and cover respectively to give with the vibrations of the spring.

In testimony whereof I affix my signature.

EARL E. CRONENWETH.
